UNITED STATES PATENT OFFICE

121,173

DESIGN FOR A REVERSIBLE LAMP

Samuel Scolaro, Auburn, N. Y.

Application March 18, 1940, Serial No. 91,037

Term of patent 3½ years

To all whom it may concern:

Be it known that I, Samuel Scolaro, a citizen of the United States, residing at Auburn, in the county of Cayuga and State of New York, have invented a new, original, and ornamental Design for a Reversible Lamp, of which the following is a specification, reference being had to the accompanying drawings, forming part thereof.

Figure 1 is a front elevational view of a reversible lamp embodying my new design;

Figure 2 is a top plan view thereof;

Figure 3 is a horizontal sectional view taken approximately on the plane of the line 3—3 of Figure 1;

Figure 4 is a side elevational view, with a portion of the shade broken away and shown in section;

Figure 5 is a vertical sectional view taken approximately on the line 5—5 of Figure 2;

Figure 6 is a rear elevational view corresponding to Figure 1; and

Figure 7 is a front elevational view on a somewhat smaller scale, of the lamp as used in an inverted position for indirect lighting, or as a container for plants, flowers, and the like.

The dominant features of my design reside in those portions represented in full lines in the drawings. The broken lines indicate the transparency of the material of which the device is formed.

I claim:

The ornamental design for a reversible lamp, as shown and described.

SAMUEL SCOLARO.
